CLAIM

The ornamental design for a holder for serving/catering trays and tins, as shown and described.

DESCRIPTION

FIG. 1 is a top, front and left-side perspective view of a holder for serving/catering trays and tins showing the new design;

FIG. 2 is a bottom, rear and right-side perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right-side elevational view thereof; the left-side elevational view being an identical mirror image thereof; and,

FIG. 8 is a perspective view of FIG. 1 shown with the lid in an open position thereof.

The broken lines in FIG. 4 depict portions of the holder for serving/catering trays and tins that form no part of the claimed design.

1 Claim, 7 Drawing Sheets
